UNITED STATES PATENT OFFICE.

JAMES C. BENNETT, OF DETROIT, MICHIGAN.

REVOLVING BOILER-TUBE BLOWER.

No. 806,626.

Specification of Letters Patent.

Patented Dec. 5, 1905.

Application filed June 30, 1905. Serial No. 267,854.

To all whom it may concern:

Be it known that I, JAMES C. BENNETT, a citizen of the United States of America, and a resident of Detroit, Wayne county, State of Michigan, have invented certain new and useful Improvements in Revolving Boiler-Tube Blowers, of which the following is a specification.

This invention relates to boiler-tube blowers; and it consists of a steam-pipe so constructed and applied to a boiler that the engineer can at any time easily and readily blow out the tubes and prevent the accumulation of soot or scale therein.

15 The invention consists of a steam-pipe centrally located in one of the tubes, provided on its inner end with a cross-arm having blower-heads located thereon, so that by rotating the pipe the blowers will be brought opposite to every and all tubes in the rear end of the boiler for injecting steam into all of them alike.

In the accompanying drawings, which illustrate my invention, Figure 1 is a side elevation of a boiler of the marine type, partly in section, showing the blowing device attached. Fig. 2 is a like view of a boiler of the stationary type, also showing my blowing device attached. Fig. 3 is an end elevation of a boiler, showing the position of the cross-arm and the blowers relative to the tubes. Fig. 4 is a sectional view of one of the blowers. Fig. 5 is a sectional view of a steam-pipe joint at the forward end of the steam-pipe, having a lever with a ratchet-and-pawl attachment for the purpose of giving rotary motion to the steam-pipe. Fig. 6 is a sectional view of a supporting-ring for the steam-pipe in the boiler-tube.

40 A represents a horizontal tubular marine boiler.

B represents a horizontal tubular stationary boiler.

C is a pipe located in one of the tubes supported in rings or collars D D. These rings have spring-legs d d at each end, by means of which the rings are held in place when forced into the ends of the tubes.

E is a cross-arm attached to the rear end of said pipe C, and upon it are attached two 50 blower-heads F F—one on the extreme end of the arm, so as to reach the outer row of tubes, as shown in Fig. 3, the other blower placed on the opposite end of the arm a sufficient distance from the end to have it rotate 55 opposite the end of the inner row of tubes. These heads are made cone-shaped and have radial bores f f for the purpose of spreading the steam-jets issuing therefrom.

G is a steam-packed elbow on the end of 60 the pipe C for connecting it with a vertical steam-pipe H, which in the case of a stationary boiler may come up through the floor.

I is a ratchet and pawl on the pipe C, having a depending hand-lever J, by which the 65 pawl is operated for rotating the pipe. These are located in the breeching at the front end of the boiler. In the case of the marine boiler a hand-wheel is placed on the pipe outside of the breeching for rotating the pipe, as 70 seen in Fig. 1. In this case the steam may be brought from an upper pipe.

It will be seen that to inject steam into all the tubes the pipe C is rotated by either the hand-wheel or hand-lever. Then the blowers 75 are successively brought opposite the tubes and thus they may be blown out in a short time.

Having described my invention, what I claim is—

In a boiler-tube blower a pipe rotatably supported in a boiler-tube, a cross-arm on the rear end of said pipe, blower-heads mounted on said arm, and a packed elbow on the forward end of said pipe C, and a ratchet and pawl 85 also mounted on said pipe, in combination for operation substantially as and for the purpose set forth.

Signed by me at Cleveland, Ohio, this 22d day of June, 1905.

JAMES C. BENNETT.
